UNITED STATES PATENT OFFICE.

MALCOLM D. RIKER, OF DOVER, NEW JERSEY, ASSIGNOR TO McKIERNAN-TERRY DRILL COMPANY, OF NEW YORK, N. Y., A CORPORATION OF NEW JERSEY.

PILE-PULLING RIG.

1,390,643.

Specification of Letters Patent. Patented Sept. 13, 1921.

Application filed July 10, 1920. Serial No. 395,334.

To all whom it may concern:

Be it known that I, MALCOLM D. RIKER, a citizen of the United States, and a resident of Dover, in the county of Morris and State 5 of New Jersey, have invented certain new and useful Improvements in Pile-Pulling Rigs, of which the following is a specification.

My invention relates to devices for pulling 10 piles, particularly sheet piling, by means of power apparatus. In brief, the device to which my invention appertains, consists of a form of inverted pile driving hammer, hung from a derrick arm, the hammer operating upward on an anvil block over which 15 passes a cable sling fastened by a clamp to the piling, thereby transmitting the blows of the hammer to the piling.

It is the object of the invention to provide 20 a well constructed, compact, simple and efficacious pile pulling rig, readily transported and set up for use and the parts of which may be easily and quickly repaired or renewed in the field.

Another object of the invention is the provision 25 of a sling or flexible connection between the piling and the operating mechanism, permitting the piling after being withdrawn, to be swung clear and laid down, after which the connection may be detached.

With the foregoing and other objects in view which will become apparent as the description proceeds, my invention resides in the combination and arrangement of parts 35 and in the details of construction described in the specification and particularly pointed out in the appended claims, it being understood that I do not limit myself to the precise embodiment of the invention herein disclosed and changes can be made within the scope of what is claimed without departing from the spirit of the invention.

In the accompanying drawings

Figure 1 is an elevation of the device in 40 position for use.

Fig. 2 is a top view of the device showing the arrangement of the cable sling, the retaining ring and other parts, with the supporting table shown in section.

Fig. 3 is a perspective diagram which 45 illustrates the relative arrangement of the cable sling and the supporting cable.

Fig. 4 is a perspective view of a false block and a retaining ring slightly separated 50 in order to show their construction clearly.

Similar reference numbers refer to similar parts throughout the several views.

In the drawings,

The numeral 10 designates the main casing of a usual form of pneumatic hammer, 60 the enlargement 9 containing the usual valves and air ports for the control and operation of the hammer piston. On the casing 10 is a ring 8 for the support of the hammer when acting in the reverse position 65 as a pile driving mechanism. At the other extremity of the casing are guides 6, 6', 7, 7' affixed thereto, the entire device being supported in the present pile pulling position by a cable 5 which passes under the casing and through the ring 8, with its ends 3, 4 looped and banded or spliced, and slipped over the hook 2 which is hung from a derrick arm by a cable 1.

Between the guides is an anvil block 20 75 which rests on a seat 19, and receives directly the blows of the hammer piston. This anvil block has a guided motion limited by the undercutting of the guides as at 17, 18. Above the anvil block is a false block 16 80 which rests directly on the anvil block and acts therewith. This false block 16 is diagonally grooved on top for the reception of the several convolutions of the cable sling, three grooves being shown for the parts 85 13, 14, 15 of the cable.

The false block 16 is also undercut at the sides 11, 12 (Figs. 2 and 4) for the reception of a retaining ring 21. This ring passes around all the cables, holding them in position, and at the same time serving to keep the hammer casing upright in its sling, there being no other means used for holding the parts together. The retaining ring 21 rests on the anvil block 20 and slides with the anvil in 90 the guides 6, 6', 7, 7'. By the use of the retaining ring shown for the purpose of holding the pulling device to the hammer, the device may be readily attached or detached from the hammer by the workman without 95 tools of any kind.

13, 14, 15 are portions of a single cable (Fig. 3) and are looped around pins 28, 29 passing between the two parts of a piling clamp 30, the loops being secured by bands 105 such as 26, 27 or by other desired means. The clamp 30 has extended portions 22, secured to the piling 25 by bolts 23, 24.

The use of cable for the pulling rig gives a material which is readily renewable by 110

the workmen in the field in case of wear or destruction, and without excessive cost.

The method of attaching the cable to the clamp 30 is a novel and important feature 5 of my invention. It will be noted that a single pin 29 passes through the loops 31 and 32 (Fig. 3) and the other pin 28 passes through the loops 33 and 34 in this embodiment of my invention. This gives six parts 10 of the cable pulling and these parts are secured by two pins in such a manner as to properly equalize and distribute the load.

The construction of the clamp 30 is also novel in that it reduces to a minimum the 15 shear on the pins 28, 29 which secure the cable, and eliminates the possibility of these pins bending so that the clamp cannot be manipulated.

Having thus described one form of applying 20 my invention, what I desire to claim is:—

1. In a pile pulling rig the combination of a power hammer, a cable sling connected therewith and means for fastening said 25 sling to a pile, whereby the action of said hammer is transmitted to said pile.

2. In a pile pulling rig the combination of a hammer having an anvil block, a false 30 block on said anvil block and coacting therewith, a cable sling passing over said false block and means for fastening said cable sling to a pile, whereby the action of said hammer is transmitted to said pile.

3. In a pile pulling rig a hammer and 35 means, comprising an anvil block and a cable sling, for transmitting the action of said hammer to a pile.

4. In a pile pulling rig a hammer, a cable sling and means for fastening said cable 40 sling to a pile comprising a two part clamp, pins passing through the two parts of said clamp and through loops in said cable sling, whereby said loops may be held between the parts of said clamp.

45 5. In a pile pulling rig, a hammer, a false block thereon, a cable sling passing over said false block and attached to a pile and means comprising a retaining ring, to hold said cable sling in coöperating position with 50 said hammer.

6. In a pile pulling rig, a hammer com-

prising an anvil block, a false block thereon, a cable sling passing over said false block and attached to a pile, a retaining ring around said cable sling and said false block, and means to limit the motion of said anvil block.

7. In a device of the character described, a hammer comprising a casing, guides projecting therefrom, and an anvil block between the guides; a supporting cable for the hammer, a false block on the anvil block, a cable sling passing over said false block and a retaining ring around said false block, and holding said supporting cable and said cable sling in position.

8. In a pile pulling rig, a hammer comprising an anvil block and guides therefor, a false block on the anvil block, a cable sling passing over said false block and attached to a pile, a supporting cable for said casing, and a retaining ring around said cable sling, said false block and said supporting cable, and resting in the undercut portions of said guides, whereby said hammer is kept in upright position in the cable sling.

9. In a pile pulling rig a hammer, a casing for said hammer and having guides, an anvil block acted upon by said hammer and in operative relation to said guides, undercut portions on said guides limiting the motion of said anvil block, a false block on said anvil block, a cable sling passing over said false block and attached to a pile, a supporting cable for said casing, and a retaining ring around said cable sling, said false block and said supporting cable and resting in the undercut portions of said guides, whereby said hammer is kept in upright position in the cable sling.

10. In a pile pulling rig a hammer, a false block thereon having its upper surface formed to receive a plurality of convolutions of a cable, a cable sling passing around the hammer and over said upper surface of the false block, and means for fastening the ends of said sling to a pile.

In witness whereof I hereunto set my hand this 9th day of July, 1920.

MALCOLM D. RIKER.
